DESIGN FOR A TRACTOR SEAT CUSHION OR SIMILAR ARTICLE

Clarence Young, Greenfield, Ohio, assignor to The American Pad & Textile Company, Greenfield,
Ohio, a corporation of Ohio

Application December 20, 1944, Serial No. 117,004

Term of patent 14 years

(Cl. D83—7)

To all whom it may concern:

Be it known that I, Clarence Young, a citizen of the United States and a resident of Greenfield,
in the county of Highland and the State of Ohio,
have invented a new, original, and ornamental Design for a Tractor Seat Cushion or Similar Article, of which the following is a specification, reference being made to the accompanying drawing forming a part thereof.

Fig. 1 is a top plan view of a tractor seat cushion or similar article showing my new design.

Fig. 2 is a bottom plan view of the cushion.

Fig. 3 is a side elevational view of the cushion.
Fig. 4 is a cross-sectional view taken on line
4—4 of Fig. 1.

Fig. 5 is a front elevational view of said
cushion.

I claim:

The ornamental design for a tractor seat
cushion or similar article, as shown.

CLARENCE YOUNG.
